Term of patent 7 years

Int. Cl. D20—03

U.S. Cl. D96—12

FIG. 1

FIG. 2

FIG. 1 is a front perspective view of a sign showing my new design, the rear being a mirror image of the front shown; and

FIG. 2 is an elevational view taken from the left side thereof.

The broken line representation of indicia and the fragmentary broken line representation of a support pole in FIG. 1 is for purposes of illustration only.

I claim:

The ornamental design for a sign, as shown and described.
